UNITED STATES PATENT OFFICE.

JEAN NICHOLS, OF DENVER, COLORADO.

DESIGN FOR A SEAT FOR COMMODES, &c.

SPECIFICATION forming part of Design No. 26,365, dated December 1, 1896.

Application filed October 21, 1896. Serial No. 609,622. Term of patent 14 years.

To all whom it may concern:

Be it known that I, JEAN NICHOLS, a citizen of the United States, residing at Denver, in the county of Arapahoe and State of Colorado, have invented and produced a certain new and original Design for a Portable Seat for Commodes and the Like; and I do declare the following to be a full, clear, and exact description of the invention, such as will enable others skilled in the art to which it appertains to make and use the same.

My invention has relation to a design for a portable seat for commodes, chamber vessels, and the like.

15 It relates to the entire configuration of the seat.

My invention relates particularly to a portable seat, as illustrated in the accompanying drawings, in which—

20 Figure 1 is a perspective view of a portable seat embodying my design. Fig. 2 is a bottom plan view. Fig. 3 is a side elevation, and Fig. 4 is a transverse section of the same.

The seat consists of an annular ring, the

upper face of which comprises a horizontal 25 plane portion 1, an inner curved edge 2, and a downwardly-extending wall 3. The outer edge 4 is likewise curved, and it thence extends inwardly to form a horizontal flange 5, thence vertically downward to form a shoulder or annular ring 6, terminating in a plane 30 bottom 7, connecting the ring or shoulder 6 with the inner wall 3.

8 represent integral ribs on the horizontal flange 5.

Having thus fully described my invention, what I claim as new, and desire to secure by Letters Patent of the United States, is—

The design for a portable seat for commodes and the like, substantially as herein 40 shown and described.

In testimony whereof I hereunto affix my signature in presence of two witnesses.

JEAN NICHOLS.
